UNITED STATES PATENT OFFICE

161,375

COMBINED TROPHY AND CLOCK

Harry S. Reinhardt, St. Louis, Mo.

Application May 11, 1949, Serial No. 2,574

Term of patent 7 years

(Cl. D42—7)

To all whom it may concern:

Be it known that I, Harry S. Reinhardt, a citizen of the United States, residing at St. Louis, in the State of Missouri, have invented a new, original, and ornamental Design for a Combined Trophy and Clock, of which the following is a specification, reference being had to the accompanying drawing, forming part thereof.

Figure 1 is a front elevational view of a combined trophy and clock showing the essential features of my new design in full lines, the representation of bowling pins and numeral "12" being merely representative;

Figure 2 is a side elevational view thereof, the outstretched arms of the human-like figure shown in Figures 1 and 3 have been omitted for convenience of illustration.

Figure 3 is a top plan view of the same.

I claim:

The ornamental design for a combined trophy and clock, as shown and described.

HARRY S. REINHARDT.
